UNITED STATES PATENT OFFICE.

JAMES E. DOYLE, JR., OF NORWALK, OHIO.

ADVERTISING SIGN.

Application filed January 6, 1928. Serial No. 244,793.

This invention relates to an advertising sign construction. The essential object is to provide an economically manufactured sign employing card, heavy paper, or the like as the main sign element, which sign, by virtue of its construction, may be very easily and quickly mounted on practically any sort of support, but particularly round members such as poles, and which will withstand 10 weather wear for a comparatively great length of time.

Other objects and features of the invention will hereinafter appear. The accompanying drawing shows the preferred form. The essential novel characteristics of the invention 15 are summarized in the claims.

In the drawing, Fig. 1 is a plan view of the device supported on a tree or pole, the support being shown in broken lines; Figs. 2 and 3 20 are cross sectional views taken substantially along the lines 2—2 and 3—3 on Fig. 1.

The common practice in mounting heavy paper or paste-board signs for advertising events such as fairs and the like, is to select 25 a suitable support, such as a fence, tree or building wall, and nail the sign to the support through the corners, usually reinforcing the sign at the nail hole by tin clips. These signs are consequently presented to the observer 30 at the angle of the supporting surface. In case of fences, the signs are presented in a very unfavorable angle to the observer as he approaches the sign, wherefore much of the advertising value is lost. This is mainly be- 35 cause for the most part, the observer passes the sign at considerable speed. It is only where the signs may be mounted on buildings or specially erected sign supports that the sign is presented in such manner as to be 40 easily read in passing. In the case of mount- 45 ing the signs on poles and trees, the signs are invariably curved in conformation to the curved surface of the support, and this detracts from the advertising value because the characters of the legend are fore-shortened at each side of the sign.

The present invention contemplates a cheap and effective means for utilizing poles and trees as a support for such advertising 50 signs, and to so arrange the elements of the sign that the printed surface may be presented full-face to the observer approaching it when he is at normal reading distance from the sign.

55 The invention utilizes, as one of its elements, a familiar reinforcement for the edge

of the card, namely, that found in calendars, and no claim is therefore made to the reinforcement per se. The invention is believed to reside in the ensemble of elements. The 60 device as shown comprises in general, a card 1, upper and lower end reinforcing members 2, and auxiliary reinforcing members 10. The card may have its character bearing surface suitably treated in the usual manner to 65 enable this surface to withstand rain.

Each edge reinforce member consists preferably of a single rectangular strip of sheet metal cooperatively folded with the edge of the sign in such manner that the strip is effectively prevented from coming off. This may be done by inserting one edge of the strip into the confines of a single edge fold 70 4 of the body, then bending the strip about the free edge of the portion 4, and doubling the 75 strip to overlap both the front and back side of the sign. The two bends in the sheet metal, as at 5 and 6, result in three panels 7, 8 and 9. The auxiliary reinforcement is in the 80 nature of a circular tab 10, secured in place, as shown in Fig. 3, wherein an edge portion 10^a of the tab is folded between the panel 7 of the strip, and portion 4 of the sign body or board. This edge folding of the tab, may, if desired, extend between all the overlying 85 portions of card and strip. The tab has an opening preferably offset from the center of the tab, as at 11, and reinforced as by a rib 11^a. The whole tab may be reinforced, if desired, by an annular rib near the outer 90 edge, designated 10^b.

To secure the sign in place on the support, the sign is placed as shown in Fig. 1, and fastening members such as nails 15 driven through the openings 11 penetrating the body 95 or card.

From the above, it will be seen that my sign construction has several unique advantages in addition to those earlier mentioned. For example, the entire device is capable of being 100 packed flat into a very small area; neither the edge reinforce nor the tabs having any considerable thickness. Further, because the tabs are on the front side of the sign and vertically aligned, it is very easy to find the tabs 105 and nail through them, locating the high point on the tree or pole in nailing the second tab after the first, simply by the sense of feeling, to avoid having to "sight" in placing the sign in upright position. Once in place, 110 the mid-portion of the sign, which is the portion most likely to give way under the

whipping effect of the wind, is so reinforced as to withstand greater strain than the remainder of the edge, because of the additional reinforcing effect of the tab.

5 I claim:-

1. As a new article of manufacture, a sign comprising a body portion of cardboard or the like adapted to be printed on and having its top and bottom edges provided with folded sheet metal reinforce devices, and a pair of vertically aligned tabs with one edge thereof folded and embraced by respective reinforce devices and extending therefrom inwardly toward each other in a plane parallel 10 to the plane of the body on the front or printed face thereof.

2. In an advertising sign, a panel formed from a single piece of flexible material, such as cardboard, a pair of sheet metal reinforce 20 devices in folded relation to the top and bottom edges of said panel, and a pair of tabs lying against the body of the panel adjacent top and bottom thereof, and having openings for the passage of nails or the like 25 through the panel, said tabs extending within the folded reinforcing members and clamped in place thereby.

3. A sign comprising a panel with suitable 30 insignia on the face thereof, one end of said panel being bent over toward the face thereof

in a **U**-form, a tab lying against the face of the panel and having its end portion bent back on itself and inserted within the **U**-part of the panel, and a metal binding strip having one extreme end lying within the folded portion of the tab, and thence bent backwardly on itself in the form of a **U** within which the folded portions of the panel and tab lie, said binding strip extending along the edge of the sign and said tab having an opening for 40 the passage of a nail through the sign adjacent the binding strip. 35

4. A sign comprising a panel with suitable insignia on the face thereof, one end of said panel being bent over toward the body thereof in a **U**-form, a tab lying against the body of the panel and having its end portion inserted within the **U**-part of the panel, and a metal binding strip extending along the edge of the sign and having one edge portion lying within the folded portion of the panel, said strip being thence bent backwardly on itself in the form of a **U** within which the adjacent portions of the panel and tab lie, said strip holding the **U** portion of the panel pressed together to clamp the tab therein. 45 50 55

In testimony whereof, I hereunto affix my signature.

JAMES E. DOYLE, JR.
